SAFETY ENVELOPE

Harry G. Brokering, Dayton, Ohio

Application January 4, 1934, Serial No. 705,249

3 Claims. (Cl. 229—82)

(Granted under the act of March 3, 1883, as
amended April 30, 1928; 370 O. G. 757)

This invention described herein may be manufactured and used by or for the Government for governmental purposes, without the payment to me of any royalty thereon.

5 This invention relates to certain new and useful improvements in envelopes, and more particularly to that class in which the contents thereof are protected against unauthorized removal. This application sets forth certain improvements over 10 the type of envelope disclosed in my pending application, filed April 17, 1933, Serial No. 666,630.

One object of the invention is to provide an envelope in which the contents are retained therein independent of the sealing flap, so that even though the seal of the flap is broken the contents cannot be removed without detection.

Another object of the invention is to provide a means by which the enclosure is adhesively connected to the envelope so that it cannot be removed therefrom without breaking the connection.

Still another object of the invention is to so design the envelope that the additional retaining means will not appreciably increase the cost of manufacture.

With these and other objects in view, the invention consists in a novel combination and arrangement of parts to be hereinafter more fully described and specifically pointed out in the claims.

In describing the invention in detail reference is had to the accompanying drawing forming a part of this specification, wherein like numerals 35 of reference indicate corresponding parts throughout the several views in which:—

Fig. 1 is a plan view of the blank from which the safety envelope is formed;

Fig. 2 is a rear elevation of the completed envelope, with sealing flap open, and retaining strap in outstretched position;

Fig. 3 is a rear elevation of an envelope with sealing flap open, and retaining strap bent over an enclosure;

45 Fig. 4 is a similar view to Fig. 2 showing a modified form of retaining strap;

Fig. 5 illustrates a form of retaining strap similar to that shown in Figs. 1, 2 and 3, but constructed as a separate unit, and

50 Fig. 6 is a side elevation of the retaining strap shown in Fig. 5.

Referring to the drawing, the numeral (1) indicates the body portion of the envelope, (2) and (2') the side flaps, (3) the lower flap, and (4) the upper adhesively coated sealing flap.

In Figs. 1, 2 and 3 is shown one form of the improved envelope in which a strap (5) is formed integral with the side flap (2'). This strap (5) is provided with adhesive on both sides thereof at its extremity (6) as shown in Figs. 1 and 2, and serves as an auxiliary retaining means for the enclosure (7), when it is bent over the same and stuck to the central or lower portion of the inside surface of the body of the envelope, or to the enclosure, or both, as shown in Fig. 3.

10 The strap (5) is preferably formed with a longitudinal opening (8) to provide narrow retaining strips (9). This is done to prevent unauthorized removal of the contents of the envelope, since any tampering with the enclosure will either tear 15 or leave marks of mutilation on the strips (9) which may be easily detected.

A modified form of retaining strap (15) is shown in Fig. 4. This type of strap consists of a narrow elongated member formed integral with the side flap (2') and adhesively coated on both sides of its upper extremity (16) so that when it is bent over an enclosure it may be stuck to the central or lower portion of the inside surface of the body of the envelope, to the enclosure or to both as with the preferred form shown in Figs. 1 to 3 inclusive. In this modified form the central longitudinal opening is omitted as the strap is made so narrow that it is readily sheared when any attempt is made to extricate the enclosure 25 from the envelope.

Another modification in the construction of the retaining straps is shown in Figs. 5 and 6. In these figures a strap (25) is shown which is provided with a central longitudinal opening (28) and lateral retaining straps (29). This strap (25) is similar in construction to strap (5) shown in Figs. 1, 2 and 3, except it is formed as a separate member, which in addition to being provided with adhesive on both sides of its upper extremity (26), 35 is also provided with adhesive at its lower extremity (27), for attachment to the inside surface of the lower flap of the envelope. The strap may then be used in a similar manner as those shown in Figs. 1 to 4 inclusive.

45 It is quite evident that the strap (15) shown in Fig. 4 could also be made up as a separate member in the same manner as the strap (25) shown in Figs. 5 and 6, and that also other slight changes might be made in the form and arrangement of the various parts described without departing from the spirit and scope of the invention, and therefore it is not desired to be limited to the foregoing except as may be required by the claims.

Having described my invention, what I claim as new and wish to secure by Letters Patent is:

1. An envelope comprising a body having integrally formed lower and side flaps adhesively united to form a packet, contents therein, and an upper flap adapted to form a closure element for said pocket, one of said flaps terminating in a centrally elongated member in the form of a loop with its end adhesively secured to the inner face of the front wall of the envelope, said upper flap being free of said elongated member and overlying the same whereby said elongated member retains the contents of the envelope when the upper flap is opened.
- 10 2. An envelope comprising a body having integrally formed lower and side flaps adhesively united to form a packet, contents therein, and an upper flap adapted to form a closure element for said pocket, one of said side flaps terminating in a centrally elongated member in the form of a loop with its end adhesively secured to the in-

ner face of the front wall of the envelope, said upper flap being free of said elongated member and overlying the same whereby said elongated member retains the contents of the envelope when the upper flap is opened.

- 15 3. An envelope comprising a body having integrally formed lower and side flaps adhesively united to form a packet, contents therein, and an upper flap adapted to form a closure element for said pocket, one of said flaps terminating in a centrally elongated strap provided with central elongated opening leaving narrow sheerable retaining strips, said strap being in a form of a loop with its end adhesively secured to the inner face of the front wall of the envelope, said upper flap being free of said elongated strap and overlying the same whereby said elongated strap retains the contents of the envelope when the upper flap is opened.
